CARBIDE WATER LIGHT AND THE LIKE

Rex A. Hunter, Bristol, Pa.

Application May 12, 1938, Serial No. 207,491

4 Claims. (Cl. 48—35)

This invention relates to gas generating and burning apparatus in which the gas is produced by reaction of a liquid with another substance: e. g., the reaction of water with calcium carbide to generate acetylene gas. For simplicity, the reactive substance is generally referred to herein as carbide, although the invention is not limited to the use of this substance. The invention is hereinafter explained in connection with a convenient form of apparatus in which a container for carbide and gas is in contact with water, or preferably afloat therein, and the water is admitted into the container to react with the carbide. For example the container may be placed afloat in a bucket of water. Thus used, the apparatus is very valuable when ample light is needed for a short time, and ordinary electric lighting is not available, as where railroad wrecks must be cleared away at night in order to restore service as quickly as possible. The apparatus may also be thrown into the sea, in an emergency, to enable a man fallen overboard to be found by boats sent to rescue him.

Important objects of the invention include the control and regulation of the admission of water to the carbide, so as to produce relatively uniform illumination over a fairly extended period, and to obviate excessive gas pressure in the apparatus, or objectionable escape of gas, and the prevention of sputtering or accidental extinction of the flame. I also aim to provide a simple, rugged, convenient form of apparatus that can be easily and inexpensively manufactured. Other features and advantages of the invention will appear from the following description of a species or form of embodiment, and from the drawing. All the features illustrated or described are of my invention, so far as novel.

In the drawing, Fig. I shows a longitudinal mid-section through a container apparatus conveniently embodying the invention.

Fig. II is a fragmentary top plan view of the container without its seal, showing its gas burner features; and Fig. III is a fragmentary view of the same end of the container from the inside, illustrating a baffle to protect the burner openings.

Fig. IV is a fragmentary mid-sectional view, on a larger scale than Fig. I, illustrating the mounting of a stand-tube in the container.

Fig. V is a plan sectional view taken as indicated by the line and arrows V—V in Fig. I.

Fig. VI is a fragmentary plan view of one end of the container, with its seal in place.

The apparatus here shown comprises an elongated can-like cylindrical container 10 of sheet-metal, such as tin, consisting of a tubular body shell with ends 11, 12 which are shown annularly embossed. At their peripheries 13, the ends 11, 12 are shown crimped securely to the edges of the body shell, and soldered thereto, both internally and externally, making tight, strong joints. Calcium carbide 14 is shown in a mass of large lumps in the lower portion of the container, around an upstanding (copper) tube 15 connected and opening through the container bottom 12. This tube 15 serves for the introduction of water into the container 10 to react with the calcium carbide 14. Around the tube 15, coaxially therewith, may be mounted a porous sleeve or screen tube 16 of larger diameter, for preventing the material 14 (or the residues from the action of the water thereon) from coming in contact with the tube 15 and clogging up its water-holes, hereinafter described. The screen tube 16 may be of sheet metal, perforated with such a multitude of fine holes as to render it foraminous. Its upper end may be contracted at 17 to fit around the tube 15 above its uppermost hole, and may be soldered to the tube 15, while its lower end may be soldered to the container bottom 12, against which it abuts.

The upper container end 11 is provided with a gas burner, preferably formed by a couple of rather fine holes 18, 18 pierced through the end 11 wall, as shown in Figs. I and II. As shown in Figs. I and III, a shield or baffle 19 is mounted directly underneath the burner openings 18, 18, being spaced below the top wall 11 and connected thereto by peripheral lugs soldered to said wall 11. This baffle 19 induces turbulence in the gas flow to the burner openings 18, 18, thereby throwing out any drops of moisture or solid particles that may be suspended in the gas and preventing such moisture from reaching the openings 18, 18 and temporarily clogging them. It also shields the openings 18, 18 from solids, liquid, or bubbles that may spit upward from the carbide. In both ways, it serves to prevent sputtering or extinction of the gas flame from causes arising inside the container 10.

As shown in Fig. I, the standtube 15 is centrally located in the container 10 and extends somewhat above the calcium carbide 14. It has openings at different levels for admitting water into the container. The high opening is above the calcium carbide 14, preferably at the upper end 20 of the tube 15, which is shown taperingly spun in and reduced in size. The low opening is considerably above the container bottom 12, con-

sisting of a couple of small holes 21, 21 drilled through the tube wall directly opposite one another. Additional openings are intermediately located, consisting of similar pairs of diametrically opposite small holes 22, 22 and 23, 23. Preferably, as shown here, the aggregate area of all the openings 21, 22, 23 and 20 is substantially less than the opening of the tube 15 at its lower end, which is shown unconstricted. As shown in Figs. I and IV, the lower end of the tube 15 extends down through a hole in the container bottom 12 and has a flange 24 beneath the latter, with its edge soldered fast to the bottom so as to make a strong, watertight joint.

15 Partly occluding the interior of the container 10, above the charge of carbide 14, there is a (circular) baffle 30. As shown, this baffle 30 occupies only the center of the container 10, with an annular interval all around between its 20 edge and the circular shell wall of the container. It is advantageous to mount the baffle 30 on the tube 15, so that it may serve to spread or distribute water from the uppermost tube opening 20 more or less uniformly in all directions upon 25 the carbide 14, besides keeping the mass of carbide in place in the lower end of the container during transportation and storage prior to use. The baffle 30 is shown as conically embossed upward, somewhat like an umbrella, with a central 30 hole fitting and tack-soldered on the tapered upper end of the tube 15. As shown at 31 in Figs. I and V, the baffle 30 may be slit or slotted inward (radially) from its periphery toward the tube 15, at a plurality of equally spaced points, 35 thus allowing water to reach the carbide in the center of the container, and also permitting the baffle to yield to upward expansion of the material 14 underneath, due to the action of the water on it. However, the interval around the 40 periphery of the baffle 30 allows such expansion to take place to some extent without any upward flexure of the baffle.

As shown in Figs. I and II, the central portions of the container ends 11, 12 are recessed 45 inward at 33 over considerable areas, inside their annular embossments, though their very centers 35, 36 (where the burner holes 18, 18 and the tube flange 24 are located) are raised outward somewhat. In other words, the ends 11, 12 are 50 annularly corrugated both outward and inward. Such a conformation not only strengthens both ends 11, 12, but also affords shelter for the central top area 35 and its burner holes 18, 18 against cross winds that might otherwise extinguish the 55 gas flame. The effectiveness of such shelter will be understood if it is realized that to extinguish a gas flame at an opening such as the holes 18, 18, the hot gases of the flame must be swept away from the very opening itself, so that there 60 is no longer anything there to heat and ignite the cool gas issuing from the opening. Moreover, the depression of the area 33 containing the burner openings 18, 18 protects the parts within these depressed areas from damage when 65 the device is handled and shipped.

As shown in Figs. I and III, I may temporarily seal over the top burner openings 18, 18 and the bottom opening to the tube 15 at the factory, to prevent deterioration of the carbide 14 70 in the container by atmospheric moisture, before the apparatus is put in service. For this purpose, sheet metal closure disks or covers 38 may be provided for the top and bottom recesses 33, and may be attached and sealed to the container ends 11, 12 around the recesses, prefer-

ably in rabbeted seats 39 which may be formed in the sloping walls of said recesses. These disks 38 are shown provided with pivoted finger-hold rings 40 mounted in hinge-ears 41 suitably attached to the disks 38, as by rivets 42. The rings 5 40 normally lie flat against the disks 38 in the shelter of the recesses 33, as shown at the bottom of Fig. I and in Fig. VI; but when the device is to be used, they are easily swung out or up, as shown at the top of Fig. I, affording good 10 holds for pulling off the closures 38. As shown in Fig. VI, the closures 38 are tack-soldered to their seats 39 at several (three) equally spaced points around their peripheries, affording ample 15 strength to allow the whole device to be carried by a ring 40, yet still allowing the closures to be pulled off with a finger inserted in the ring.

The joints between the closure disks 38 and their seats 39 may be sealed air and water tight by any suitable means, such as "liquid porcelain" 20 applied after attachment of the disks. The whole exterior of the container 10 is preferably painted after completion of the device. Besides sealing the closure disk joints, the paint also secures the rings 40 at the hinge-joints and against 25 the disk surfaces, so as to hold them seated in the recesses 33, as shown at the bottom of Fig. I and in Fig. V, until they are purposely pulled up as shown at the top of Fig. I.

For the convenience of those wishing to employ my invention, and in illustration of how to proportion the tube 15 and the associated features, I give specific dimensions of one apparatus that has been used with very satisfactory results:

Over-all length of container 10	inches	13 1/4
Diameter of container	inches	5
Diameter of burner holes 18, 18	inch	3/2
Distance apart of burner holes, on centers	inch	40
Length of tube 15	inches	6 5/8
Internal diameter of tube 15	inch	1 5/8
Internal diameter of reduced top opening 20	inch	3 3/2 45
Diameters of holes in tube 21, 22	inch	3/2
Height of lowest holes 21, 21 above lower end of tube	inches	1 1/8
Height of next holes 22, 22 above lower end of tube	inches	2 1/8
Height of next holes 23, 23 above lower end of tube	inches	4 1/8
Weight of carbide charge 14	pounds	4 1/2
Depth of carbide charge 14 in container	inches	6 1/2
Diameter of umbrella-baffle 25	inches	3 3/4
Height of baffle edge above container bottom 12	inches	6 1/2

These dimensions are not intended to define or limit the invention, but merely for purposes of illustration. Experience has confirmed the substantial correctness of the hole-sizes stated to give a maximum relatively unfluctuating candle power with a minimum loss of gas.

In manufacture, the charge of carbide 14 is conveniently placed in the container 10 after the tubes 15 and 16 have been set and soldered fast; then the baffle 30 is soldered on the tube 70 as shown; and finally the top end 11 is put on and secured to the container shell. The lumps of carbide 14 soon adhere together where they are in contact, owing to the effects of atmospheric moisture.

A mode of use and operation of the apparatus is as follows:

The seal closures 33, 38 having been removed, the device is placed top end up in any convenient body of water, preferably not less than some 15 inches deep—as in a large bucket. A device of the dimensions above given initially floats about 9 inches deep in the water, so that the water-line will be about 2½ inches above the uppermost opening 20 at the top end of the tube 15. Momentarily, therefore, water may stream in on the carbide 14 from all the openings 21, 22, 23 and 20, giving rise to abundant evolution of acetylene gas; and in a fraction of a minute, this gas is discharging at the openings 18, 18, and can be lighted with an ordinary match. The amount of gas initially generated exceeds the capacity of the burner 18, 18 and a pressure builds up in the container 10. As soon as this pressure exceeds that of a water-head of about 2½ inches, which is the height between the external water level indicated in Fig. I and the level of the topmost opening 20, the inflow of water at the uppermost opening 20 ceases, reducing the rate of water supply and gas evolution very greatly. Generally, the evolution of gas in the container 10 still exceeds the capacity of the burner 18, 18, developing a higher pressure that forces the water down in the tube 15 below the openings 23, 23 and even to or below the openings 22, 22 or 21, 21, thus further reducing the rate of water supply to the carbide 14 and the evolution of gas. Increase of gas pressure in the container 10 increases the discharge of gas at the burner 18, 18. In this manner, a condition of at least approximate equilibrium is established between the rate of gas discharge and the rate of water inflow and gas evolution, with the water at a more or less nearly constant level in the tube 15, the dimensions of the burner openings 18, 18 and of the standtube openings 21, 22, 23, and 20 as stated above being suitably correlated for this.

In this initial condition of equilibrium, the gas pressure in the container 10 due to reaction of water admitted through the lower holes 21 (say) with the fresh carbide in the bottom of the container counter-balances the upward pressure of water in the standtube 15, and keeps this water below the higher standtube openings 22, 23, 20 (say). As the bottom layer of carbide below the holes 21 becomes more and more worked out and waterlogged, the container 10 sinks deeper and deeper in the surrounding water. During this increasing immersion of the container 10, such increase as may occur in the rate of inflow at the holes 21 (due to the increased hydrostatic head) tends to compensate for the tendency toward reduced reactivity of the carbide in the bottom layer. Accordingly, the evolution of gas and the gas pressure in the container 10 are sufficiently maintained until the water rising in the tube 11 reaches and passes through the next higher standtube openings 22 (say). This, of course, considerably augments the total effective area of opening available for the admission of the water, although the hydrostatic head at the openings 22 is not so great as that at the openings 21.

As the container 10 sinks deeper in the water, the available and effective area of water-admission opening is further augmented when the water reaches the standtube openings 23, and, finally, the top standtube opening 20. All the time, however, the water level in the tube

15, the number of openings 21, 22, 23, 20 available for admitting water, and the rate of water inflow and of gas evolution remain under the regulative control of the gas pressure in the container 10: if gas is at any time evolved more rapidly than it can escape at 18, 18, the pressure in the container increases and forces the water down in the tube 15, reducing the number of holes accessible to the water and the rate of inflow and gas evolution until equilibrium 10 is restored. If, occasionally, some gas escapes downward through the tube 15 into the water around the container 10, the amount will be so trifling that no danger of explosion or the like will arise.

Experience has shown that the device will afford a steady light, which will burn for about two hours and a quarter or more before the carbide 14 becomes worked out.

It is to be observed that when the aggregate area of the openings 20 and 21, 22, 23 from the interior of the container 10 into the tube 15 is somewhat less than its bore and the opening at its lower end, as above described, the tube functions partly as a water-column in which the gas pressure in the container 10 is balanced against the difference in water level around the container and in the tube. Thus the possible gas pressure in the container 10 is limited to a head of about nine inches of water; for if this were ever exceeded, the gas would escape downward through the tube 10, absolutely preventing (for the time) any inflow of water to generate more gas, and afford protective shelter for the peripheral joints during transportation and handling of the device. Under test, it has been found impossible to obtain a gas pressure amounting to 1 lb. per sq. in. in the container 10, at any stage of operation. This would not be so, of course, if the opening from the tube 15 to the water outside (beneath) the container were greatly constricted, so that gas pressure might build up in the container faster than it could be relieved through the tube. A sufficiently free opening from the interior of the container 10 into the tube 15 above the water therein is also important.

It is further to be observed that while the baffle 30 keeps the carbide 14 in place in the lower end of the container 10 during transport, storage, and handling, it allows the soft lime left from the reaction of the water with the carbide to expand outward and upward past its outer edge. Nevertheless, the baffle 30 checks the expansion and keeps the lumps of good carbide in place, thus to a degree controlling the exposure of the carbide to the water and the speed of gas formation. The slots 31 allow the baffle 30 to yield under moderate pressure due to the expansion of the carbide by reaction with the water, thus obviating any extreme compression of the carbide which might unduly check further penetration of water into it, or even burst the container 10. Accordingly, the baffle 30 coacts with the standtube openings 21, 22, 23, 20 (which are correlated with the burner openings at 18, 18 as above indicated) in assuring a desirably constant evolution of gas.

Having thus described my invention, I claim:

1. In a carbide water light, the combination with a carbide and gas container charged with carbide and buoyant so as to float in water, and gas burner means associated with said container and supplied with gas therefrom, of a standtube in said container having a constant inlet through

the container wall for admitting water into the tube, and extending up in the carbide, and also having a series of restrictive openings at different elevations for supplying water from the tube to the carbide, the total area of all said water supply openings being less than the area of said water inlet into the standtube, so that the number of said supply openings accessible to the water controls the rate of inflow of water to the carbide, and the total area of opening of said burner means being many times less than the total area of the water supply openings from the standtube to the carbide, so that initially the gas pressure in the container due to reaction of the water admitted through the lower of said supply openings with the fresh carbide in the bottom of the container counterbalances the upward pressure of water in the standtube and keeps the water in said tube below the higher supply openings, while as the carbide in the bottom of the container becomes worked out and water-logged, and the container sinks lower in the water, the gas pressure in the container allows the water in the standtube to rise and pass through the higher supply openings.

2. The invention as set forth in claim 1 wherein the gas burner means is of smaller capacity than the top standtube opening.

3. In a carbide water light, the combination with a carbide and gas container charged with carbide and buoyant so as to float in water, and gas burner means associated with said container and supplied with gas therefrom; of a standtube in said container having a constant inlet through the container wall for admitting water into the tube, and extending up in the carbide, and also having a series of restrictive openings

at different elevations for supplying water from the tube to the carbide, the total area of all said water supply openings being less than the area of said water inlet into the standtube, so that the number of said supply openings accessible to the water controls the rate of inflow of water to the carbide, and the total area of opening of said burner means being many times less than the total area of the water supply openings from the standtube to the carbide, so that initially the gas pressure in the container due to reaction of the water admitted through the lower of said supply openings with the fresh carbide in the bottom of the container counterbalances the upward pressure of water in the standtube and keeps the water in said tube below the higher supply openings, while as the carbide in the bottom of the container becomes worked out and water-logged, and the container sinks lower in the water, the gas pressure in the container allows the water in the standtube to rise and pass through the higher supply openings, and a baffle occluding the interior of said container above said charge of carbide and yieldingly resisting its upward expansion due to the action of water on it, and thus controlling the permeability and exposure of the carbide to the water, and the speed of gas formation.

4. The invention as set forth in claim 3 wherein said baffle comprises a sheet metal disc around the standtube attached to the same, but free of attachment to the container wall and at intervals slit inward from its periphery toward the standtube, and thus rendered yieldingly resistant to upward expansion of the carbide.

REX A. HUNTER.
